S. SCHLESINGER

UMBRELLA

Filed Nov. 15, 1921

UNITED STATES PATENT OFFICE.

SIGMUND SCHLESINGER, OF NEW YORK, N. Y.

UMBRELLA.

Application filed November 15, 1921. Serial No. 515,384.

To all whom it may concern:

Be it known that I, SIGMUND SCHLESINGER, a citizen of the United States, and resident of New York city, borough of Manhattan, in the county of New York and State of New York, have invented certain new and useful Improvements in Umbrellas, of which the following is a specification.

My invention relates to improvements in means for retaining umbrellas closed and their tip cups in cooperation with the tips of the ribs, and has particular reference to improvements in the class of umbrellas set forth in Letters Patent granted to me November 20, 1917, No. 1,247,159.

In my said Letters Patent I have set forth means to retain and release the tip cup as well as the runner, and the object of my present invention is to improve retaining means for the runner and the tip cup to assure the release of the runner and the tip cup from the rib tips practically simultaneously, whereby the umbrella may be opened, or may open automatically when it is provided with springs for opening it.

My invention comprises novel details of improvement that will be more fully herein-after set forth and then pointed out in the claims.

Reference is to be had to the accompanying drawings forming part hereof, wherein—

Figure 1 is a detail view illustrating parts of the umbrella in an open position;

Fig. 2 is an enlarged detail view of the umbrella retaining devices;

Figs. 3 and 4 are sections substantially on line 3, 3, in Fig. 2, illustrating the retainer and other parts in different positions, and

Fig. 5 is a detail perspective view illustrating my improvements.

Similar numerals of reference indicate corresponding parts in the several views.

The tubular umbrella rod 1 may be of any well known construction to which the ribs 2 are pivoted at 3. The braces 4 are shown pivoted to the ribs at 5 and at 6 to the runner 7 in any usual manner. The runner 7 is shown provided with a fitting 8 to which the braces 4 are pivoted, and to which the springs 9 are shown connected at 10, said springs being also connected with the ribs for causing automatic opening of the umbrella in a well known manner. A stop 11 on rod 1 may be provided to engage fitting 8 to limit opening of the umbrella (Fig. 1). The foregoing parts may be of

any well known construction. The tip cup or tip retainer 12 is shown in hollow or open ended form to receive the tips of the ribs and having a tubular portion at 13, 60 which is illustrated as slidably mounted upon runner 7 between the fitting 8 and the outer end of the runner. A coiled spring 15 surrounds the runner and is adapted to bear against the tip cup to move it against the 65 umbrella handle, said spring also bearing against the fitting 8. The tip cup is shown provided with a tubular extension 16 (on the side opposite the tubular portion 13) that surrounds the spring 15, and at 17 is 70 a sleeve entering tubular extension 16 and surrounding spring 15, which sleeve is united to or formed with the fitting 8. The extension 16 and sleeve 17 telescope and the latter serves to guide the former while they both 75 inclose and hide the spring. The tendency of spring 15 under expansion is to move the tip cup or retainer away from the rib tips to the position shown in Fig. 3 to release the tips, the tubular portion 13 of the tip 80 cup then abutting against stop 14 on the runner to limit outward movement of the tip cup. The parts above described are substantially similar to corresponding parts set forth in my aforesaid Letters Patent. 85

My improved means for retaining and releasing the runner and the tip cup are as follows: A keeper 19 shown in the form of a projection or finger carried by a resilient or spring acting member 20, is retained 90 at 21 within tubular rod 1, which rod is shown provided with a slot 22 for the passage of projection 19 and a finger piece 23 projecting through rod 1 from member 20, the member 20 being adapted to bend when 95 the finger piece is pushed inwardly. The stop 14 is shown hollow and transversely disposed at its wall 14^a to engage the adjacent edge 19^a of keeper 19 to retain the umbrella closed, the edge 19^b of projection 19 being shown curved to slidably receive 100 the inner edge of wall 14^a as the runner is pushed to the closed position, whereby the projection 19 will move inwardly to enable the wall 14^a to pass beyond edge 19^a of projection 19, as illustrated in Fig. 3. Associated with keeper 19 the member 20 carries a movable stop or finger to retain the tip cup in engagement with the rib tips. The said movable stop is indicated at 24 110 pivotally supported at one side of member 20 at 26. The stop 24 is provided with a

projection or finger 27 adapted to pass through the slot 22 and through a slot 28 in the runner when the latter is in the closed position and retained by retainer 19, in which position finger or projection 27 will oppose the adjacent end of tubular portion 13 of tip cup 12 to retain the latter in position to engage the rib tips. The stop 24 is also adapted at its portion 24^a, adjacent to keeper 19, to engage the inclined portion 14^b of stop 14. The stop 24 is controlled by a spring 29 carried by member 20, which spring is shown in the form of a wire attached to member 20 at the holes 30 therein, (Fig. 3), and also attached to stop 24 by means of apertured lug 31 thereon. The tendency of spring 29 is to tilt stop 24 respecting member 20, (Fig. 5), to withdraw finger 27 from position of engagement with the runner when the umbrella is being closed. When the tip cup is not retained by the projection or finger 27, the spring 15 will push the tip cup away from its position of cooperation with the rib tips.

When the umbrella is being closed the runner will be pulled as usual, the tip cup being in the advanced position. The outer end of wall 14^a will engage the curved portion 24^a of stop 24 to tilt the same upon member 20 to tend to advance finger 27, and said wall will also engage projection 19 to depress it with member 24 to enable the wall 14^a to pass beyond said projection and member, the extension 13 of the tip cup passing over projection or finger 27, at which time member 20 will be somewhat depressed within rod 1 by reason of the simultaneous engagement of stop 24 with wall 14^b and projection of finger 27 with the tip cup, although retainer 19 will be in position to engage and retain wall 14^a to keep the umbrella closed, substantially as shown in Fig. 3. When the rib tips are to be retained by the tip cup, said ribs are gathered together and held so that the tip cup may be slid along the runner, to receive the rib tips in the cup, substantially as shown in Fig. 3, the spring 15 then being placed under compression. When the tip cup has been moved so that its extension 13 passes beyond the finger or projection 27 the latter will pass through slot 28 in the runner to a position in front of the outer end of extension 13, (Fig. 3), to prevent spring 15 from pushing the tip cup, whereby to retain the rib tips in the tip cup. Projection 27 will be retained in the position shown in Fig. 3 by reason of the outward spring tendency of the member 20 in connection with the contact of part 24^a of stop 24 with the inclined part 14^b of stop 14, the tension of member 20 preponderating over the tension of the spring 29. When it is desired to open the umbrella it is merely necessary to press finger piece 23 inwardly, whereupon stop 24

will be moved with member 20 and projection 27 will be moved away from in front of extension 13, the spring 29 tending to tilt stop 24 as the member 20 moves with said stop, the part 24^a operating against the part 14^b as a fulcrum, so that the tip cup will be quickly released upon operation of member 20, the continued inward movement of the latter causing retainer 19 to release wall 14^a, so that the runner will be free to permit opening of the umbrella. When springs 9 are used the umbrella will automatically open when released from retainer 19, and if such springs are not used the umbrella may be pushed open by hand.

A feature of my improvement is that the tip cup will be quickly released upon pressing member 20 inwardly within rod 1 so that the ribs will be released from the tip cup approximately just before, and not later than, the release of the runner from retainer 19, which has the advantage of preventing release of the runner from retainer 19 before the tip cup has released the rib tips, so that, in an automatically opening umbrella, the tension of springs 9 will not be exerted against ribs held by a tip cup.

When the parts are in the position in Fig. 3 finger or projection 27 will be stopped by the metal at the adjacent end of slot 28 against the pressure of spring 15 through extension 13 to prevent said extension from sliding over finger 27 to release the rib tips. The rear upper corner of member 20 is reduced or rounded to not interfere with wall 14^a when the umbrella opens.

Having now described my invention, what I claim is:

1. The combination of a rod and ribs pivotally connected therewith, with a runner connected with the ribs, a tip cup provided with a tubular portion slidable on the runner to move therewith, said runner having a slot over which the tubular portion of the tip cup may pass, and a keeper movably carried by the rod to cooperate with the runner to retain the latter in a closed position, the keeper being provided with a member movably connected with the keeper adapted to pass through said slot in the runner, and means to cause the movable member to oppose said tubular portion of the tip cup to retain the latter in coaction with the rib tips.

2. The combination of a rod and ribs pivotally connected therewith, with a runner connected with the ribs, a tip cup provided with a tubular portion slidable on the runner to move therewith, said runner having a slot over which the tubular portion of the tip cup may pass, and a keeper movably carried by the rod to cooperate with the runner to retain the latter in a closed position, the keeper being provided with a movable member having a finger to project

through said slot in the runner and having a portion to cooperate with the runner, and means to cause said member to rock to engage the runner and to permit the runner to travel relatively to said member.

3. The combination of a rod and ribs pivotally connected therewith, with a runner connected with the ribs, a tip cup provided with a tubular portion slidable on the runner to move therewith, said runner having a slot over which the tubular portion of the tip cup may pass, and a keeper movably carried by the rod to cooperate with the runner to retain the latter in a closed position, the keeper being provided with a movable member having a finger to project through said slot in the runner and having a portion to cooperate with the runner, and a spring cooperative with said member adapted to retain its projection out of relation to the runner, when the umbrella is open, the member having a portion to be engaged by the runner to move said projection through the slot in the runner to permit said projection to oppose the tubular member of the tip cup when the keeper retains the runner and the tip cup is in position to retain the rib tips.

4. In an umbrella, the combination of a rod and ribs pivotally connected therewith, with a runner connected with the ribs and provided at its outer end with a transverse wall and with an angularly disposed wall, a tip cup provided with a tubular portion slidable on the runner to move therewith, said runner having a slot over which the tubular portion of the tip cup may pass, and a keeper carried by the rod adapted to engage the transverse wall of the runner to retain the umbrella closed, a movable member associated with the keeper and having a portion to engage said inclined wall of the runner and a projection adapted to

the runner and a projection adapted to pass through the slot of the runner adapted to cooperate with the tubular portion of the tip cup to retain the latter in coaction with the rib tips when the umbrella is closed, and means to retain said projection out of relation to the runner when the umbrella is open.

5. In an umbrella, the combination of a rod and ribs pivotally connected therewith, with a runner connected with the ribs and provided at its outer end with a transverse wall and with an angularly disposed wall, a tip cup provided with a tubular portion slidable on the runner to move therewith, said runner having a slot over which the tubular portion of the tip cup may pass, and a keeper carried by the rod adapted to engage the transverse wall of the runner to retain the umbrella closed, a movable member associated with the keeper and having a portion to engage said inclined wall of the runner and a projection adapted to pass through the slot of the runner adapted to cooperate with the tubular portion of the tip cup to retain the latter in coaction with the rib tips when the umbrella is closed, and a spring cooperative with said member to tilt it to retain its projection out of the path of the runner when the umbrella is open, said inclined wall of the runner being cooperative with said member to cause its projection to pass through the slot of the runner and cooperate with the tubular portion of the tip cup to retain the latter in coaction with the rib tips when the umbrella is closed.

Signed at New York city, in the county of New York, and State of New York, this 7th day of November, A. D. 1921.

SIGMUND SCHLESINGER.
